CLAIM

We claim the ornamental design for a winter clog, as shown and described.

DESCRIPTION

FIG. 1 is a right perspective view of a winter clog showing our new design;

FIG. 2 is a right side elevation view thereof;

FIG. 3 is a left side elevation view thereof;

FIG. 4 is a top plan view thereof;

FIG. 5 is a bottom plan view thereof;

FIG. 6 is a front view thereof; and,

FIG. 7 is a rear elevation plan view thereof.

The broken lines shown are for illustrative purposes only and form no part of the claimed design.
